[57] CLAIM

The ornamental design for a toilet paper caddy, as shown and described.

DESCRIPTION

FIG. 1 is a perspective view of a toilet paper caddy showing our new design;

FIG. 2 is a right side elevational view with the left side being a mirror image thereof;

FIG. 3 is a front elevational view thereof;

FIG. 4 is a rear elevational view thereof; and,

FIG. 5 is a top view thereof.

The portions of the figures shown in broken lines are for illustrative purposes only and form no part of the claimed design.
